(57) **CLAIM**

The ornamental design for a pillowcase with an offset seam aperture, as shown and described.

DESCRIPTION

FIG. 1 is a front perspective view of a new design for a pillowcase with an offset seam aperture.

FIG. 2 is a top view of a new design for a pillowcase with an offset seam aperture.

FIG. 3 is a rear view of a new design for a pillowcase with an offset seam aperture.

FIG. 4 is a front view of a new design for a pillowcase with an offset seam aperture.

FIG. 5 is a bottom view of a pillowcase with an offset seam aperture.

FIG. 6 is a left side view of a new design for a pillowcase with an offset seam aperture; and,

FIG. 7 is a right side view of a new design for a pillowcase with an offset seam aperture.

The broken lines depict portions of the pillowcase that form no part of the claimed design.

The broken lines crossing claimed surfaces depict claimed stitching.
